UNITED STATES PATENT OFFICE

ALLAN A. ADAMSON, OF ROCHESTER, NEW YORK, ASSIGNOR, BY MESNE ASSIGNMENTS,
TO AUTOKRAFT BOX CORPORATION, OF LIMA, OHIO, A CORPORATION OF DELAWARE

CIGAR BOX

Application filed July 11, 1928. Serial No. 291,882.

The present invention relates to cigar boxes, an object of this invention being to make it possible to reduce the time required in the manufacture of cigar boxes. Another object of the invention is to provide a lid having a hinging strip attached thereto to be nailed to the rear wall of the box body.

To these and other ends, the invention consists of certain parts and combinations of parts, all of which will be hereinafter described: the novel features being pointed out in the appended claims.

In the drawings:

Fig. 1 is a sectional perspective of one embodiment of the invention;

Fig. 2 is a perspective view of the lid employed in connection with the embodiment shown in Fig. 1;

Fig. 3 is a sectional perspective of another embodiment of the invention;

Fig. 4 is a perspective view of the lid employed in the embodiment illustrated in Fig. 3;

Fig. 5 is a plan view of the blank employed as a wrap for the lid shown in Figs. 3 and 4; and

Figs. 6, 7, 8, 9 and 10 are fragmentary sectional views of five other embodiments of the invention.

Prior to this invention cigar boxes have been manufactured by completing the box body and edging or covering the same and completing the lid and edging the latter while it is separated from the box body. There-

after the lid is hinged to the box body by a hinging strip of textile material adhesively secured to the outer face of the lid near the rear edge of the latter and to the outer face of the rear wall of the body near the upper edge

of the latter. After adhesively securing the hinging strip, it has been necessary to lay aside the lidded box until the adhesive has dried, thus preventing handling of the box for some hours and requiring considerable

space for storage of the boxes during drying. According to this invention this drying period is eliminated, and the box with the lid secured thereto is, after the lidding operation, immediately in condition for further operations on the box.

This invention may be carried out in a large number of ways.

In the embodiment shown in Figs. 1 and 2, the box body 1 is made of card board and is wrapped by a cover 2 which may have suitable labels printed thereon. The lid 3 is also formed of laminated paper board which is cut or slit at 4 near one edge to form a hinging strip 5 connected to the lid by one or more of the laminations common to the lid and the hinging strip. A lid wrap 6 is now adhesively applied to the lid to cover the outer face of the lid with its edges 7 turned over the inner face of the lid. The lid in this condition now has the hinging strip 5 secured to the upper edge of the rear wall of the box body by small nails 8 driven through the hinging strip and into the rear wall, the hinged portion 9 between the strip and the lid being positioned adjacent the outer edge of the rear wall so that the lid can swing to closed position and overlie the strip. The rear edge of the cover as well as the hinging strip is now covered with an edging piece 10 which extends across the hinged portion 9 and serves to strengthen such hinged portion. A lid label 11 is now adhesively secured to the inner face of the lid and has an extension 12 which projects over the hinged portion 9 to strengthen the latter and downwardly over the inner face of the hinging strip onto that portion of the body wrap 2 which extends onto the inner face of the box body.

In the embodiment shown in Figs. 3, 4 and 5, the box body 1 is formed from laminated material such as paper board and has the body wrap 2 secured over the outer face thereof and extending over the upper edges over the inner face of the paper board body. The lid member 3 is formed from paper board cut or scored to provide a hinging piece 5 connected to the lid proper by a hinged portion 9 formed by laminations of the paper board material from which the lid and hinging piece are made. The wrap 6^a is adhesively applied to the lid before this lid is attached to the box body and covers the outer face of the lid as well as extending about the edges of the lid onto the inner face of the lid.

This wrap also has an extension 13 which extends over the rear edge of the lid and the rear edge of the hinging strip. Nails 8 are driven through the hinging strip and into the upper edge of the rear wall of the box body. An inside label 11 is now adhesively secured to the inner face of the lid, extends over the hinging portion 9 of the hinging strip, over the upper and inner face of the hinging strip and downwardly onto the inward turned edge of the box body wrap. This inside label 11 also tends to strengthen the hinging portion 9. This construction eliminates one of the operations shown in Figs. 1 and 2 as the hinging strip may be covered on its outer face by the same operation that applies the wrap to the outer face of the lid.

In the embodiment shown in Fig. 6, the box body 1, which may be made of any suitable material, is completed and also the lid 3 with its hinging piece 5^b before the lid is attached to the box body. The lid is formed from laminated material such as paperboard as in the other embodiment and the hinging piece 5^b is cut from the material of the board by slitting the latter so as to provide a hinging portion 9^b formed by laminations of the board. The hinging portion 9^b, in this instance, is positioned at the inner upper corner of the hinging piece 5^b and at the rear upper corner of the lid 3 so that the lid does not overlap the hinging piece or strip when the cover is in closed position.

In the embodiment shown in Fig. 7, the box body 1 is formed of any suitable material while the lid 3 is formed of paper board which is reduced at its rear edge to form a hinging strip 5^c from one or more of the laminations of the board, thus providing a hinging strip of substantially the same thickness as the hinging portion 9^c. This strip 5^c is secured by nails 8 to the upper edge of the rear wall of the box body 1 so that the hinging portion 9^c lies in immediate proximity to the lower rear edge of the lid 3.

In the embodiment shown in Fig. 8, the box body is formed of any suitable material while the lid 3 is formed of paper board and the hinged strip 5^d is formed by cutting the board so that one or more of the laminations thereof provide the hinging strip. The hinging strip 5^d is secured by nails 8 to the outer face of the rear wall of the box body instead of to the upper edge of the rear wall as shown in Fig. 7.

In the embodiment shown in Fig. 9, the box body is formed in any suitable manner while the lid 3^e is formed preferably of wood. A hinging strip 5^e also formed of wood is secured to the lid 3^e while the latter is detached from the box body by means of a piece 9^e formed of cloth or other suitable material and is adhesively secured to the lid and the hinging strip. Nails 8 pass through the hinging

piece 5^e and into the upper edge of the rear box body 1 to hold the lid to the box body.

In the embodiment shown in Fig. 10, the box body 1 is formed in any suitable manner while the lid is laminated being formed of a piece of wood 14 which has on its inner face a sheet 15 of paper board, the sheet being extended at 16 beyond the edge of the wooden piece 14 to provide the hinging piece. This hinging piece is nailed at 8 to the upper edge of the rear wall of the box body so that the hinging portion 9^f will lie at the rear lower edge of the lid and the latter will overlie the hinging strip 16 when in closed position.

In Figs. 6 to 10, the manner of wrapping or edging the box body and lid is not shown but it will be understood that any suitable wrap, edging or labels may be employed. It is preferred however to use the wrap, edging or labels to strengthen the hinge, as in the embodiment shown in Figs. 1 or 3.

In all embodiments of the invention, the box body and the lid are completed before the lid is attached to the box body by the hinging strip. When the hinging strip is nailed to the upper edge of the rear wall of the body, said wall is made of less height than the front wall, the thickness of the hinging strip being substantially equal to the difference in heights between the two walls. The wraps and/or labels tend to strengthen the hinged connection. After the box and lid are nailed together, the box is immediately ready for other operations, thus doing away with the lapse of time between these operations.

This type of cover or lid hinge has special advantage when used in connection with a cigar box having an outside wrapping means which covers the outer side walls of the box, extends over the upper edges of the side walls onto the inner faces of said side walls as shown in Figs. 1 and 3 of the drawings. This is due to the fact that a hinging strip made of textile material and adhesively secured to the lid or cover adjacent the rear edge of the latter and also to the upper edge of the rear wall, is not effective as a good hinge when secured to paper of which the outside wrapper is made. The outside wrapping of cigar boxes with paper is coming into favor due to the fact that a wrap of this kind can be put on by machinery, doing away with the old type of hand edging and also to the fact that cigar boxes are being made of cheaper material, such as cheap wood or paper board or both. With this type of outside wrapping comes the difficulty of attaching the cover or lid to the box body effectively by a cloth or textile strip.

What I claim as my invention and desire to secure by Letters Patent is:

1. A cigar box comprising a box body, a separately formed flat lid for the body formed of laminated material cut in its outer face adjacent its rear edge to form a hinging strip

the hinge of which is adjacent the inner face of the lid, the hinging portion being formed by some of the laminations of the material, nails fastening said hinging strip to the rear wall of the box body.

5 2. A cigar box comprising a box body, a lid formed of laminated material, a hinging strip arranged at the rear edge of the lid and having laminations in common with those of the lid, said strip being secured to the upper edge of the rear wall of the box body and having the lid overlying the same when in closed position.

10 3. A cigar box comprising a box body having its front wall of greater height than its rear wall, a lid, a hinging strip projecting from the rear edge of the lid and having a thickness substantially equal to the difference in height between the front and the rear wall of the box body a length equal to the length of the cover and a width equal to the thickness of the rear wall, said strip being secured to the upper edge of the rear wall and having the lid overlapping it when the lid is 20 in closed position.

25 4. A cigar box comprising a box body having its rear wall of less height than its front wall, a lid, a hinging strip of substantially the same thickness as the lid, having a continuous hinged connection flush with the inner face of the lid, said strip resting on the upper edge of the rear wall of the box, and fastening devices passed through the strip into the rear wall of the box body.

30 5. A cigar box comprising a box body, a lid, a hinging strip, flexibly connected to the lid along the rear edge thereof, said strip having a height equal to the thickness of the lid and a width equal to the thickness of the rear wall of the box body, and means for securing the hinging strip to the upper edge of said rear wall.

35 6. A cigar box comprising a box body and a lid scored adjacent its rear edge to provide a hinging strip flexibly connected therewith, said strip being secured to the upper edge of the rear wall of the box body and having a height equal to the thickness of the lid, and a width equal to the thickness of said rear wall.

40 7. A cigar box comprising a box body, and a lid formed of laminated material and scored adjacent its rear edge to provide a hinging strip flexibly connected therewith by one or more of the laminations, said strip being secured to the upper edge of the rear wall of the box body and having a height equal to the thickness of the lid, a width equal to the thickness of said rear wall and a length equal to the length of the lid.

45 8. A cigar box comprising a box body having its front wall of greater height than its rear wall, a lid scored adjacent its rear edge to provide a hinging strip flexibly connected therewith, said strip having a height equal to

the difference in height between said front and rear walls, and having a width equal to the thickness of said rear wall, and means for securing said strip to the upper edge of said rear wall.

50 9. A cigar box comprising a box body having its front wall of greater height than its rear wall, a lid formed of laminated material and cut adjacent its rear edge to provide a hinging strip flexibly connected therewith by one or more of the laminations, said strip having a height equal to the difference in height between said front and rear walls, and having a width equal to the thickness of said rear wall, and means for securing the strip to the upper edge of said rear wall.
